UNITED STATES PATENT OFFICE.

ANDREW MORRISON, OF PITTSBURG, PENNSYLVANIA.

METALLIC RAILWAY-TIE.

No. 821,951.

Specification of Letters Patent.

Patented May 29, 1906.

Application filed January 9, 1905. Serial No. 240,338.

To all whom it may concern:

Be it known that I, ANDREW MORRISON, of Pittsburgh, Allegheny county, Pennsylvania, have invented a new and useful Metallic Railway-Tie, of which the following is a full, clear, and exact description, reference being had to the accompanying drawings, forming part of this specification, in which—

Figure 1 is a cross-section of track provided with my improved tie. Figs. 2 and 3 are respectively top and bottom plan views of the tie, and Figs. 4, 5, and 6 are partial side elevations showing modified forms.

My invention relates to the class of metallic railway-ties of I-beam form, and is designed to decrease the weight of the tie while providing ample strength.

Heretofore in the manufacture of metallic ties of I-beam form the tie has been cut from a rolled section of I-beam form. In such case it is extremely difficult to provide base-flanges which are sufficiently wide to receive and distribute the applied loads. Moreover, if I-beam forms are used with wide flanges the flanges are of the same width throughout the length of the tie and the tie is liable to become "center-bound"—that is, the weight being near the ends, so that they are forced downwardly, there would be a tendency to rock on the center portion of the tie, which would remain higher, no load being applied direct at this point. Such ties also are of greater weight than desirable.

My invention is designed to overcome these difficulties and to provide a lighter tie of ample strength which will avoid the tendency to become center-bound and may be insulated from the rail. It is further designed to prevent wear of the upper face of the tie, and thereby greatly lengthen its life, and to allow a slight up-and-down movement of the rail relatively to the tie.

In the drawings, referring to the form of Figs. 1, 2, and 3, 2 is the tie-body, which preferably consists of an I-beam having top and bottom flanges of equal width. A commercial I-beam of, say, about three inches in width of flange is preferably used. In order to give the proper width of bearing-surface through the end portions of the tie, I rivet to the bottom flanges of the I-beam end plates 3, which are of much greater width than the base of the beam. For example, if the beam has a three-inch base the plates may be ten

inches in width. These plates preferably extend from the ends of the tie toward its center, so as to provide about equal length on each side of the rail-base, leaving the tie ends open or substantially so. In this form I show chafing-plates 4, interposed between the base of the rail 5 and the upper face of the I-beam. These wear-plates have a length greater than the width of the rail-base and are also preferably wider than the top of the I-beam, though the latter feature may or may not be used, as desired.

In using the structure in an insulated section of track I place a flat layer of insulating material 6 between the chafing-plate and the top of the I-beam tie, this preferably being coextensive with that portion of the I-beam which is covered by the wear-plate. This position of the insulating material avoids its rapid cutting out. The wear-plate is preferably secured by bolts 7, extending through the insulated material, through the wear-plate, and through clips 8, which rest on the wear-plate.

The clips are provided with lugs 9, projecting over the base-flanges of the rail. These lugs are preferably formed so that a clearance of, say, one-sixteenth or one-eighth of an inch is provided between their lower faces and the top face of the base-flange of the rail. This clearance is to prevent the vertical motion of the tie in the ballast, which follows from the wave motion imparted to the rail as the train moves over it. It is desirable to leave the tie stationary in the ballast and allow the rail to move up and down slightly on the tie, as in the case of wooden ties, where the spikes are lifted slightly by the rail. Instead of this clearance I may employ clips which bear directly on the flange, but are provided with springs 9^a, as shown in Fig. 4, between the clip and the nut, or the springs may be placed within the clip and bear on the rail, as shown at 9^b in Fig. 5. In either case the rail is allowed to rise slightly from the tie, thus avoiding the moving up and down of the tie in the ballast.

In order to more firmly hold the clips in place to partially take the strain from the screw-bolts 7 and to reduce the wear of insulation, I may provide the wear-plate at one or both ends, with upwardly-projecting lugs or shoulders 10, which may extend along the entire edge or be in the form of separated

lugs. The rear ends of the clips preferably bear against these shoulders of the plate. The shoulder may be arranged on the chafing-plate so as to bear against the edge of the rail-base instead of against the clip.

5 In order to complete the insulating of the tie from the rail, I employ a thimble or sleeve 11, of fiber or insulating material, which surrounds the bolt and extends from 10 the flat layer of insulating material on the tie up to an insulating-washer 12, beneath the nut 13. This thimble extends through the chafing-plate and through the clip.

15 The structure may of course be used without insulating it from the rail. Thus in Fig. 4 I show a structure similar to that of Fig. 1, similar parts being designated by similar numerals with the letter *a* applied, the insulation being done away with. In Fig. 5 I 20 show a form similar to that of Fig. 4, similar parts being designated by similar numerals with the letter *b* applied, except that the shoulders on the chafing-plate are done away with. In Fig. 6 I show a form where the rail 25 rests directly on the tie, the letter *c* being applied to similar numerals.

I do not claim herein the insulating means described and shown, as the same is described and claimed in my divisional copending application.

30 The advantages of my invention result from securing the wider end plates to the base of the I-beam, since this decreases the amount of metal in the tie while giving ample bearing-surface beneath its end portions. This also avoids a tendency to become center-bound. Further, from the use of the chafing-plates, which I believe to be new in connection with the metallic tie, these chafing-plates will 35 receive the chafing and wear due to movements of the rail, and after they become worn, so as to allow the rail to cant or tilt slightly, they may be removed and new ones inserted. The life of the tie is thus greatly lengthened.

40 45 The forming of the clips so that they allow a slight up-and-down movement of the rail on the tie avoids overstraining of the parts under the wave motion and allows the tie to remain firmly seated in the ballast.

50 55 The chafing-plate may be provided with shoulders at one end only or with no shoulders, the form of the clips may be varied, and many other variations may be made without departing from my invention.

55 I claim—

1. A metallic tie of I-beam form having open ends, and plates wider than the I-beam secured to the end portions of its base; substantially as described.
- 60 2. A metallic tie of I-beam form having plates wider than the I-beam secured beneath its end portions extending about equidis-

tantly on either side of the rail-base; substantially as described.

3. A metallic tie consisting of a single I- 65 beam having a metallic chafing-plate between the rail-base and the tie, said plate being secured to the tie by connections extending through its flanges, and separate clips and bolts for securing the rail to the tie; substantially as described. 70

4. A metallic tie having a metallic chafing-plate between the rail-base and the tie, said plate being secured to the tie by connections extending through the top of the tie and being wider than said top, and means for securing the rail to the tie; substantially as described. 75

5. A flanged metallic tie having a metallic chafing-plate secured to its top flanges and of 80 greater length in the direction of the longitudinal axis of the tie, than the width of the rail-base, and separate clips resting on the chafing-plate and securing the rails in place; substantially as described.

6. A metallic tie consisting of an I-beam having a chafing-plate secured to its top flanges and provided with a shoulder or shoulders extending crosswise of the plate; substantially as described. 85

7. A metallic tie having a chafing-plate secured to its top and provided with a shoulder or shoulders extending crosswise of the plate and spaced apart from the rail-base, and a separate clip fitting between the shoulder 90 and rail-base; substantially as described. 95

8. A railway-track having metallic ties, rails rigidly supported on the ties, and a clip device securing the rails to the ties, said device being arranged to allow a slight up-and-down movement of the rail relative to the tie; substantially as described. 100

9. The combination with a metallic tie, rails rigidly supported on the ties, and of a clip device for holding the rail, said device being arranged with a clearance-space between it and the flange of the rail to allow of a slight up-and-down movement of the rail relative to the tie; substantially as described. 105

10. A metallic tie having a chafing-plate 110 secured to its top and provided with a shoulder or shoulders extending crosswise of the plate and spaced apart from the rail-base, and separate clips fitting between the shoulders and rail-base, said clips having bolts securing them to the tie; substantially as described. 115

In testimony whereof I have hereunto set my hand.

ANDREW MORRISON.
